UNITED STATES PATENT OFFICE.

ADELMER M. BATES, OF CHICAGO, ILLINOIS.

DESIGN FOR A BAG OR SACK.

SPECIFICATION forming part of Design No. 31,268, dated July 18, 1899.

Application filed September 26, 1898. Serial No. 691,945. Term of patent 14 years.

To all whom it may concern:

Be it known that I, ADELMER M. BATES, a citizen of the United States, residing at Chicago, in the county of Cook and State of Illinois, have invented and produced a new and original Design or Useful Shape for a Bag or Sack, of which the following, in connection with the accompanying drawings, is a full, clear, and exact specification.

5 In the said drawings, Figure 1 is a side elevation of a bag or sack, showing my design; and Fig. 2 is an end view looking down from the top.

The leading features of my design consist 5 of a bag or sack having one end cut on the bias-line A and the irregular line of stitching B C D extending lengthwise of one side at the corner and thence across the end of the

bag and finally down the opposite side to the diagonally opposite corner, the line of stitching B being arranged parallel with and at a distance from the longer side of the bag.

The main body portion of the bag-pattern when viewed from the side, as in the drawings, is substantially rectangular at the end opposite the biased end A.

Having thus described my invention, what I claim as new therein, and desire to secure by Letters Patent, is—

The design for a bag or sack substantially as herein shown and described.

A. M. BATES.
